UNITED STATES PATENT OFFICE

156,074

DESIGN FOR A DRESS ENSEMBLE

Urleene Chaplain, Riddings Ridge, Conn.

Application April 18, 1949, Serial No. 2,111

Term of patent 3½ years

(Cl. D3—26)

To all whom it may concern:

Be it known that I, Urleene Chaplain, a citizen of the United States, residing at Riddings Ridge, in the county of Fairfield and State of Connecticut, have invented a new, original, and ornamental Design for a Dress Ensemble, of which the following is a specification, reference being had to the accompanying drawing, forming part thereof.

Fig. 1 is a front view of the dress ensemble, showing my design,

Fig. 2 is the rear view of the dress ensemble shown in Fig. 1,

Fig. 3 is a fragmentary front view of the dress member of the ensemble shown in Fig. 1,

Fig. 4 is a fragmentary rear view thereof, and

Fig. 5 is a fragmentary front view of the coat member of the dress ensemble, illustrating the collar portion in closed position.

The balance of the skirt is conventional.

I claim:

The ornamental design for a dress ensemble, substantially as shown and described.

URLEENE CHAPLAIN.
